* cited by examiner

Primary Examiner—Susan E Krakower(74) *Attorney, Agent, or Firm*—Wenderoth, Lind & Ponack, L.L.P.(57) **CLAIM**

The ornamental design for a pendant, as shown and described.

DESCRIPTION

FIG. 1 is a front view of the invention;

FIG. 2 is a rear view of the invention;

FIG. 3 is a left side view of the invention;

FIG. 4 is a right side view of the invention;

FIG. 5 is a bottom view of the invention; and,

FIG. 6 is a top view of the invention.

The broken lines illustrate portions of the pendant which form no part of the claimed design.
